(57) CLAIM

The ornamental design for a garment, as shown and described.

DESCRIPTION

FIG. 1 is a front view of a garment according to the design; FIG. 2 is a rear view thereof;

FIG. 3 is a right side view thereof;

FIG. 4 is a left side view thereof;

FIG. 5 is a front perspective view thereof;

FIG. 6 is a rear perspective view thereof;

FIG. 7 is a front view thereof shown in an environment of use; and,

FIG. 8 is a rear view thereof shown in an environment of use.

The portions of the garment shown in broken lines in FIGS. 1-8 form no part of the claimed design. The broken line outline of the partial human figure in FIGS. 7-8 assists in illustrating how the garment may appear when in a position of use, but forms no part of the claimed design.
